UNITED STATES PATENT OFFICE.

WILLIAM H. SWARTZ, OF YORK, PENNSYLVANIA, ASSIGNOR TO GENERAL MACHINE WORKS, OF YORK, PENNSYLVANIA.

SHARPENER.

Application filed February 12, 1924. Serial No. 692,306.

My invention relates to improvements in sharpeners for edge tools, implements, and skates. It is ideally adapted for sharpening skates since it produces a hollow ground 5 edge, which is highly desirable, and which is not readily obtained by a file, or any device using a file.

In its preferred form, my sharpener comprises a plurality of axially arranged disc 10 cutters loosely mounted on a shaft or pin, carried by a supporting member preferably in the form of a housing. The sharpener is adapted to be either held in the hand and drawn over the skate, or fastened securely 15 in a position near the ground so that a person wearing skates may, without removing the skates from the feet, draw the runner of each skate over the cutters.

In the drawing—
20 Figure 1 is a transverse sectional view of the sharpener on line 1—1 of Fig. 2;
Figure 2 is a longitudinal sectional view on line 2—2 of Fig. 3;
Figure 3 is an end view of the sharpener 25 in sharpening position on a skate;
Figure 4 is an end view with one guide removed and the other guide arranged in a position adapted to sharpen bevel edges on tools etc.;
30 Figure 5 is a front view of one of the guide members;
Figure 6 is a fragmental view similar to Fig. 2, of a modified form without the separating washers;
35 Figure 7 is a fragmental view similar to Fig. 2, of a modified form with plain discs having no projections, and with separating washers;
Figure 8 is a view showing the manner in 40 which the cutter discs tilt to sharpening position when a skate is drawn over them in the direction of the arrow;
Figure 9 is a front view of one of the sharpening discs shown in Fig. 2; and
45 Figure 10 is a section of Fig. 9 on line 10—10.

My sharpener preferably comprises a housing or main body J so shaped that the sides K almost enclose the cutter or sharpener discs b, thus protecting the hand when using as shown in Fig. 3. The top of the housing is formed into a foot L with a hole m at each end for attachment in permanent position, when so desired. Mounted in the 55 ends O of the housing, is a shaft or pin d

carrying a plurality of sharpening discs b separated by spacing or separating washers c. The cutters and washers have free spaces a between them to allow for the change of position as shown in Fig. 8. The holes p 60 in the cutters and washers are much larger than the shaft d as shown in Fig. 1 to permit the cutters to assume the slanting or tilted position of Fig. 8.

When used for sharpening skates, (Fig. 3) guide members e are secured to ends O by screws g passing through slots f, thus providing a guide space or slot A, which can be made of suitable width to accommodate the exact thickness of any blade, by sliding 70 the guide members laterally to each other on screws g and securing in the desired adjustment by tightening said screws g.

When used for sharpening bevel edges on tools, etc., one guide e is removed from 75 each end O of the housing and the remaining guides are tilted, and secured in any desired position (Fig. 4) by screws g at each end. Thus at each adjustment of guides e, three angles h are provided for sharpening purposes.

When plain sharpening discs q are used as shown in Fig. 7 it is desirable to separate them with washers c. But when sharpening discs with projections or pressed out portions r are used, washers may be used as in Fig. 2 or they may be dispensed with as in Fig. 6 since the projections r act to keep the main body portions of the sharpening discs spaced from each other. Another advantage of these pressed out projections is that when the discs are piled together to carbonize them, the projections keep the edge portions of the discs separated from each other and permit the entire edge portions to become carbonized. Thus when hardened, the cutting edges will be hard all over, and therefore free from soft spots.

I claim:

1. A sharpener comprising a support, a single row only of axially arranged sharpening discs tiltably mounted on said support, and non-sharpening guide means in cooperative relation with said discs.
2. A sharpener comprising a support, a single row only of axially arranged sharpening discs tiltably mounted on said support, and adjustable guide means on said support.
3. A sharpener comprising a support, a

plurality of sharpening discs tiltably mounted on said support, and guide means on said support adjustable to provide a slot of various widths.

5. 4. A sharpener comprising a support, a plurality of sharpening discs mounted on said support, and guide means on each end of said support adjustable to provide a slot of various widths.

10. 5. A sharpener comprising a support, a plurality of sharpening discs mounted on said support, and guide means on said support comprising a plurality of members adjustable relatively to each other to provide

15. a slot of various widths, one or more of said members having a slot in an edge spaced from said adjustable slot.

6. A sharpener comprising a support, a

plurality of sharpening discs mounted on said support and washers mounted on said support between the sharpening discs, said discs having lateral projections.

7. A sharpener comprising a support, axially arranged sharpening disks tiltably mounted on the support, and means mounted 20 in proximity to the disks and adapted to be swung into position for guiding a tool over the edges of the disks.

8. A sharpener comprising a support, axially arranged sharpening disks tiltably 25 mounted on the support, and a guide lug mounted in proximity to and extending beyond the disks, adapted to be swung into position for guiding a tool over the edges of the disks.

WILLIAM H. SWARTZ.
